CLAIM

The ornamental design for a handbag, as shown and described.

DESCRIPTION

FIG. 1 is a front perspective view of a first embodiment of a handbag showing my new design;

FIG. 2 is a front perspective view of an enlarged portion of FIG. 1 in an open configuration;

FIG. 3 is a front elevational view of FIG. 1;

FIG. 4 is a rear elevational view thereof;

FIG. 5 is a left side elevational view thereof;

FIG. 6 is a right side elevational view thereof;

FIG. 7 is a top plan view thereof; and

FIG. 8 is a bottom plan view thereof;

FIG. 9 is a front perspective view of a second embodiment of a handbag showing my new design;

FIG. 10 is a front elevational view thereof;

FIG. 11 is a rear elevational view thereof;

FIG. 12 is a left side elevational view thereof;

FIG. 13 is a right side elevational view thereof;

FIG. 14 is a top plan view thereof; and,

FIG. 15 is a bottom plan view thereof.

The dash-dash broken lines depict stitch lines and portions of the handbag that form no part of the claimed design. The dot-dot-long dash broken lines in FIGS. 1-2 represent the bounds of the enlargement taken from FIG. 1 and form no part of the claimed design.
